ELECTRICAL POSITIONING SYSTEM

George H. Phelps, Catonsville, Md., assignor to
Westinghouse Electric Corporation, East Pittsburgh,
Pa., a corporation of Pennsylvania

Application February 5, 1943, Serial No. 474,829

6 Claims. (Cl. 172—239)

1

This invention relates to electrical positioning systems and, more particularly, to a selective control of circuit elements from a remote point.

Positioning systems of the type to which this invention particularly relates include a motor drive rotatable in both directions which is coupled to the driven element in such manner that the movement of the latter can be set to various predetermined positions. In these systems, it is essential that the driven element should be accurately positioned along a circular path to any preselected position, by rotation in either clockwise or counterclockwise direction. Control systems heretofore used generally employ a split disc in cooperation with the driving motor which rotates simultaneously with the driven element. There is also a suitable electrical or mechanical clutch mechanism to disengage the motor when the driven element reaches the selected position. On the split disc are placed a number of contacts, each defining one selected position of the driven element. The insulating space which separates the two halves forms the dividing line between the two directions of rotation of the motor. The free space between the two segments cooperates with the contacts so that when any one of the contacts through which a circuit is completed to the motor reaches this space it will open the circuit.

When a split disc is used the rotation in each direction is confined to 180°. If rotation beyond that is desired up to nearly 360° each half of the split disc may be replaced by individual contact discs carrying contact segments which make a complete revolution for each direction of rotation.

While this type of remote control has been widely used, it has the disadvantage that for very accurate positioning a very accurate and small clearance must exist between the two halves of the split disc segments. The slightest momentum of the turning disc augmented by the momentum of the motor may cause overriding, whereby upon contact with the other segment a reversal of the motor is effected. This condition creates hunting or oscillating around the desired point. Moreover, the accuracy of positioning is limited by the width of the insulating space between the discs which in practice has to be wide enough to prevent hunting, and thereby allows appreciable differences in the actual stopping position.

The present invention overcomes these disadvantages when such systems are used for the positioning of switches or other circuit components,

2

wherein each position represents equal angular displacements over the path described by the arc of rotation. This is accomplished by the addition of a cam switch driven by the motor which permits further rotation of the motor after the desired positioning has been established.

Another advantage of the positioning system herein described is that the usual clutch between the motor and the driven element can be eliminated by utilizing a novel drive in the form of a Maltese-cross gear, so that the accuracy of the setting is determined thereby.

A particular feature of the invention resides in an extremely compact mechanical assembly which is easily adapted to effect the positioning of any number of selector switches accurately to any preselected stop.

Another feature of the invention, as will be seen when considering its mechanical details, resides in the drive mechanism for the Maltese-cross gear which maintains a rigid contact position for the selector switches driven thereby.

A marked advantage of the system herein described is its freedom from temperature variations in that prior to the movement of the actuated element no actuating motor may start under no-load condition and may run for a definite time freely. In this manner operation is secured when temperature conditions adversely affect the motor speed and power.

Other features and advantages will be apparent from the following description of the invention, pointed out in particularity by the appended claims, and taken in connection with the accompanying drawings, in which:

Figs. 1, 2 and 3 show three views of the compact driving mechanism as a unit which can be attached to any desired number of selector switches; Fig. 4 shows a schematic circuit arrangement for the control of the positioning mechanism in combination, by way of example, with the tuning mechanism of a radio receiver to a number of preselected frequencies.

Referring to the drawings, in the views of Figs. 45 1, 2 and 3, the driving motor 1 is shown to be mounted in a frame 2, the motor having a shaft 3 carrying a worm 4. The latter drives the worm gear 5, the shaft 6 of which runs transverse to the frame 2 in bearings 7 and 8. Secured to the shaft 6 and driven thereby is the lock wheel 9 carrying the pin 10 for driving the Maltese-cross wheel 12. On the other side of the gear 5, the shaft 6 carries the cam 13, the surface of which engages the movable member 14 of the hold-over switch 15. The Maltese-cross wheel 12

drives the shaft 17 at one end, and at the other end it rotates the circuit control switch 18 and the connecting switch 20 for the hold-over switch 15. The shaft 17 protrudes sufficiently to permit coupling thereto the selector switches which the device is intended to position. In other words, to the shaft 17 is connected the driven element of the positioning system.

The mechanical features should be observed in these figures for a clearer understanding of the system when considering the operation thereof in connection with the various electrical controls. It is seen, taking particularly Figs. 2 and 3 into consideration, that as the motor shaft 3 revolves the lock wheel 9 is turned by the worm gear 5. The lock wheel 9 carries the locking member 11 which engages the corresponding peripheral face of segment 16, of the Maltese-cross wheel 12. As long as the member 11 engages the surface of the segment 16, the Maltese-cross wheel 12 is locked in position. At every revolution of the lock wheel 9, the pin 10 engages the slot 19 between the segments 16 and will drive the wheel 12 one segment in either direction depending upon the direction of rotation of the wheel 9. When the pin 10 engages the slot 19, the cutout portion of the member 11 unlocks the wheel 12, permitting movement thereof. It is to be noted that once the pin 10 leaves the slot 19, the wheel 9 is free to rotate without affecting the firm position of the Maltese-cross 12. In this manner, as will be explained later, the motor may continue its rotation over a comparatively long segment in the circular path of the pin 10, and may be stopped anywhere along this segment without interfering with the succeeding positioning of the Maltese-cross 12. This is an important feature and instrumental in the absolute accuracy of each step in the positioning of the shaft 17.

Referring now to the operation of the system and observing the circuit shown in Fig. 4, it is seen that the important mechanical elements are shown in perspective and the electrical circuit is schematically represented. For the purpose of clear illustration, the control switches and the various mechanical elements are spaced far apart, and particularly the shaft 17 is shown extended. Coupled to the shaft is shown, by way of example, a set of rotary switches for the remote actuation of the tuning of a radio receiver. The electrical positioning device in accordance with this invention is well adapted for use in connection with radio receivers, and for this reason it was chosen to illustrate its operation in connection with a radio receiving system. It is to be understood and can readily be seen that, in place of the tuning arrangement of the radio receiver, other types of rotary switches may be actuated for a variety of purposes, such as selecting different electrical circuits. While there are only two switches shown, any number may be employed as long as they are to be actuated simultaneously. The switches may also have any number of contacts provided that the Maltese-cross wheel segments are accordingly proportioned and the size of the circuit control switch 18 allows the placement of the number of riding contacts desired side-by-side along the two operating segments 22 and 22' respectively. To avoid unnecessary complication of the circuit, there are only three contacts shown, sufficient it is believed for a thorough understanding of the operation of the system.

The terminals A and B indicate the connection to a source of power for driving the

motor 1. This source may be either alternating or direct current. The motor is of the dual-field type, having fields 23 and 24. One terminal of each field connects to one side of the incoming supply line in series with the armature or rotor which contacts brushes 25 and 26. The other terminal of field 23 connects through lead 27 to the rider 28 of the circuit control switch 18 engaging the segment 22, and also through lead 29 to the upper contact of the hold-over switch 15. Similarly, the other terminal of field 24 connects through lead 30 to the rider 31 which engages segment 22' of the circuit control switch 18, and also to the lower contact of the hold-over switch 15. Displaced around the switch 18 are the contacts 32, 33 and 34, equidistantly placed corresponding to the number of steps which the positioning system is to make in its intended operation. Connected in parallel with the above-mentioned contacts are the contacts 35, 36 and 37 of the connecting switch 20, the rider of which is connected through lead 38 to the moving contact 14 of the hold-over switch 15. The contacts 39, 40 and 41 of the manual selector switch 42 connect also to contacts 32, 33 and 34, respectively. The manual selector switch 42 may be placed at any desired location and completes the current path to the source in that its rider 43 is connected to the terminal B of the supply.

The radio receiver shown here comprises a simple amplifier and detector circuit tunable by means of the fixed condensers 47, 48 and 49 in the amplifier stage and the fixed condensers 50, 51 and 52 in the detector stage. Each of these condensers is indicated to be variable for a particular setting to tune the receiver to a desired station. Selector switch 53 connects any one of the condensers 47, 48 or 49 to the grid 55 of the vacuum tube 56, tuning thereby the grid circuit comprising the secondary 57 of the radio frequency input transformer 58. Similarly, the selector switch 54 connects any one of the condensers 50, 51 or 52 in shunt with the secondary 59 of the coupling transformer 60. The various circuit elements of the radio receiver have no bearing on the invention herein described and need not be considered in detail. Suffice it to say that when switches 53 and 54 connect corresponding contacts, the radio receiver is tuned to receive a selected station.

Describing the operation, let us assume that the entire system is at rest. It is seen that following the circuit from the A terminal, the motor fields 23 or 24 are not energized, since the connection to the field is broken in that neither switch 18 nor switch 15 is closed to the contacts selected by switch 42. Thus the center contact 40 of the switch 42 was chosen as the desired position when the system was last operated. Following the connection to the center contact 33 of the switch 18, we see that the circuit is broken by the insulation between the segments 22 and 22'. Furthermore cam 13 is in such position that the moving contact 14 of the switch 15 is between the upper and the lower contacts.

Let us now turn the manual selector switch 42 to the position whereby its rider 43 engages the contact 41. Following the circuit from the B terminal, we see that the current will flow through the contact 34 of the switch 18 and finds a path along the segment 22' to the contact 31 and through lead 30 to the field 24 and through the motor to the terminal A. It should be noted also that the rider of the switch 20 does not engage the contact 37, so that the moving

arm 14 of the switch 15, is not connected to the current source. The purpose of the switch 20 will be better understood when the operation of the system becomes clear and will be explained hereafter in greater detail.

We have seen that the field 24 become energized, when the switch 42 was moved to energize contact 41. The connections of the motor fields are so made that when the field 24 is energized, the motor will turn the worm 4 so as to rotate the worm-gear 5 in the proper direction whereby the Maltese-cross wheel 12 moves the shaft 17 so that the contact 34 of the circuit control switch 18 shall be placed between the segments 22 and 22'. In accordance with the operation in the manner chosen it is seen that the rotation of the worm gear 5 must be counterclockwise as indicated by the arrow, since movement of the drive pin 10 in this direction will rotate the Maltese-cross wheel 12 in a clockwise direction. It should be noted here that as the worm gear 5 rotates and the pin 10 approaches the Maltese-cross wheel 12, the cam 13 will lift the moving arm 14 of the switch 15 so that it engages the upper contact thereof. However, this in no way influences the rotation of the motor 1 in the direction indicated in that, as can be seen in tracing the circuit, the field 23 is not connected to the source, because the circuit through contact 14 and upper contact 15 is broken at contact arm 20 of the switch 20 and also at contact 39 of the switch 42. As the drive pin 10 moves the Maltese-cross wheel 12 one step and shaft 17 is turned thereby, the switch 18 will be moved so that the segment 22' no longer engages the contact 34. The latter will be now in the same position as the contact 33 was previously, that is, the circuit therethrough will be broken. At the same time, the switch 20 will engage contact 37. The switches 53 and 54 are now also positioned so that condensers 47 and 50 are placed across the respective circuits of the receiver. The instant when this occurs the drive pin 10 will be just ready to leave the slot, and the motor would stop since the contact 34 is not in engagement with the segment 22', and the circuit is broken between contacts 34 and 31. However, the operation of the hold-over switch 13 assures continued rotation of the motor and also, of course, of the pin 10 of the lock wheel 9. The reason for this is that the cam 13 will now offer the smaller diameter of its contours to the moving arm 14 of the hold-over switch 15, so that the lower contact thereof is in engagement. In tracing the circuit, we see that the current starting from the terminal B will flow through contact 41 of the switch 42, contact 37 of the switch 20, through lead 38 and the lower contacts of the hold-over switch 15 through the field 24. The rotation will continue until the cam 13 reaches the original starting position shown, whereby the arm 14 of the hold-over switch 15 is again in the mid-position between the upper and lower contacts. Whatever momentum the motor may have had, including the momentum of the worm gear 5 and lock wheel 9 which would tend to continue rotation of the motor even after the arm 14 of the hold-over switch 15 breaks the circuit, will not affect the accuracy of the setting of the driven elements in that the Maltese-cross wheel stays in locked position over a substantial travel of the drive pin 10. The stopping surface 44 of the cam 13 has sufficient length to allow for the movement due to momentum when the arm 14 is lifted from

the lower contact to break the circuit to the motor.

Considering now the operation of the switch 20, it will be seen that it is intended to control the connection of the arm 14 of the hold-over switch 15 to the supply circuit in such manner that when the manual selector switch 42 is placed to any desired contact for the next ensuing operation, connection to the arm 14 of the hold-over switch 15 is broken until the shaft 17 is moved to the selected position. Then contact of the hold-over switch arm 14 is again established through the new setting of the switch 20.

I claim as my invention:

- 15 1. In an electrical positioning system, switching means adapted to be positioned in definite steps over a series of contacts, a motor for driving said means, an energizing circuit for said motor including a current source and a circuit control switch in series therewith operated in conjunction with the positioning of said means, said circuit control switch determining also the direction of rotation of said motor, a selector switch adapted to be placed at a remote point for selecting at will the positioning of said switching means to any one of the number of said series of contacts, said selector switch completing the energizing circuit through said control switch to said motor and a hold-over switch maintaining said energizing circuit closed until the positioning of said switching means is fully completed and after said control switch reaches its open circuit position.
- 20 2. In an electrical positioning system, switching means adapted to be positioned in definite steps over a series of contacts, a motor for driving said means, an energizing circuit for said motor including a current source and a circuit control switch in series therewith operated in conjunction with the positioning of said means, said circuit control switch determining also the direction of rotation of said motor, a selector switch adapted to be placed at a remote point for selecting at will the positioning of said switching means to any one of the number of said series of contacts, said selector switch completing the energizing circuit through said control switch to said motor and a hold-over switch operated by a cam driven by said motor for maintaining said energizing circuit closed until the positioning of said switching means is fully completed and after said control switch reaches its open circuit position.
- 25 3. In an electrical positioning system, switching means adapted to be rotatably positioned in definite angular steps over a series of contacts, a reversible motor for driving said means, an energizing circuit for said motor including a current source and a circuit control switch in series therewith operated in conjunction with the rotation of said means, said circuit control switch determining also the direction of rotation of said motor, a selector switch adapted to be placed at a remote point for selecting at will the positioning of said switching means to any one of the number of said series of contacts, said selector switch completing the energizing circuit to said motor, and a hold-over switch operated by a cam driven by said motor for maintaining said energizing circuit closed until the rotation of said switching means is fully completed to the selected contact and after said control switch reaches its open circuit position.
- 30 4. In an electrical positioning system, switch-

ing means adapted to be rotatably positioned in definite equidistant steps over a series of contacts, a reversible motor for driving said means, an energizing circuit for said motor including a current source and a circuit control switch in series therewith operated in conjunction with the rotation of said means, said circuit control switch determining also the direction of rotation of said motor, a selector switch adapted to be placed at a remote point for selecting at will the positioning of said switching means to any one of the number of said series of contacts, said selector switch completing the energizing circuit in series with said control switch to said motor and a hold-over switch in shunt with said control switch for maintaining said energizing circuit closed until the positioning of said switch means is fully completed and after said control switch reaches its open circuit position.

5. In an electrical positioning system, driving means comprising a reversible motor, driven means, a drive between said motor and said driven means including means for positioning said driven means to a fixed step of angular displacement for each complete revolution of said

drive in either direction, an electrical control circuit for said motor including means for determining the direction of rotation of said driven means and for selecting a particular step of displacement thereof, and control means for completing the revolution of said drive to substantially the same stopping point after said driven means is positioned to a selected step.

6. In an electrical positioning system, driving means comprising a reversible motor, driven means, a drive between said motor and said driven means including a Maltese-cross coupling for positioning said driven means to a fixed step of angular displacement for each complete revolution of said drive in either direction, an electrical control circuit for said motor including switching means actuated by said driven means for determining the direction of rotation of said driven means and for selecting a particular step of displacement thereof, and control means for said motor for completing the revolution of said drive to substantially the same stopping point after said driven means is positioned to a selected step.

GEORGE H. PHELPS.
